UNITED STATES PATENT OFFICE

99,563

DESIGN FOR A HAIR CURLER

William H. Schmitt, St. Paul, Minn.

Application July 12, 1935, Serial No. 57,604

Term of patent 14 years

To all whom it may concern:

Be it known that I, William H. Schmitt, a citizen of the United States, residing at St. Paul, county of Ramsey, and State of Minnesota, have invented a new, original, and ornamental Design for Hair Curler, of which the following is a specification, reference being had to the accompanying drawing, forming part thereof.

I claim:

The ornamental design for a hair curler as shown.

WILLIAM H. SCHMITT.
